MASONRY CUTTER

Eugene P. Sanders, Allendale, N. J., assignor to
 Champion Manufacturing Co., St. Louis, Mo.,
 a corporation of Missouri

Application November 15, 1946, Serial No. 710,097

7 Claims. (Cl. 125—13)

1

This invention relates to machines of the rotary cutter type and particularly to machines for cutting masonry blocks, ceramics and the like.

An important object of the present invention is greatly to simplify and improve upon the construction and operation of machines of the rotary cutter type whereby the cutting of masonry and ceramic blocks or the like may be accomplished more economically and with accuracy and convenience.

It is an object also to provide a machine of the above character in which the rotary cutter and mounting means therefor is capable of a range of positional adjustment for accommodating various sizes of masonry or ceramic objects to be cut, and in which the rotary cutter is mounted or otherwise arranged for yielding or floating movement relative to its mounting means during cutting operation to compensate for variations in feed and cutting loads.

Another object of the invention is to be found in the construction and arrangement of a machine for cutting masonry or ceramic objects in which a cutter operating power head assembly is mounted for movement independently of the rotary cutter mounting means and in a manner to maintain its operative driving connection therewith throughout the range of adjustment of the latter.

Other objects of this invention are to be found in the simplified arrangement and low cost construction of a machine of the present character rendering the same conveniently collapsible for quick and easy packaging as a unit, in the provision of means for reducing or suppressing the objectionable dissemination of dust and particles usually produced in the cutting operation as by the provision of a fluid circulated medium which is directed into the zone of action of the cutter and is thereafter collected for recirculation, and in the arrangement and use of the fluid collector as a guideway for the support of a carriage assembly upon which the masonry or ceramic objects are placed for cutting thereof.

The foregoing objects as well as many advantages of the present machine will be more specifically pointed out in the following detailed description relating to a presently preferred embodiment thereof as illustrated in the accompanying drawing, in which:

Fig. 1 is an assembly view, in side elevation of the rotary cutter type machine;

Fig. 2 is a similar view illustrating the machine in its collapsed condition ready for unitary packaging;

2

Fig. 3 is a top plan view of the machine shown in Fig. 1;

Fig. 4 is an enlarged and fragmentary sectional elevational view taken at line 4—4 of Fig. 3;

5 Fig. 5 is a further sectional elevational view of the machine taken at line 5—5 of Fig. 1, and

Fig. 6 is a sectional elevational view taken at line 6—6 in Fig. 1.

In the drawing and particularly Figs. 1 and 3 10 thereof, the improved machine may be seen to include a table-like supporting structure 7 for a power head 8, a cutter head 9 and a carriage 10 upon which the ceramic or masonry block A or other object to be cut is placed.

15 More specifically, the supporting structure 7 (Fig. 1) is constituted of a shallow, open top tank 11, at each of the corners of which a leg member 12 is suitably pivotally connected. The longitudinally spaced pairs of legs at each side are 20 rigidly braced against collapsing movement by suitable angularly directed bracing elements 13 pivoted to the legs and releasably attached in pairs to the side wall of the tank 11 at a common securing element 14. This arrangement readily permits the table structure to be collapsed, as 25 shown in Fig. 2, as the legs 12, upon release of bracing elements from means 14, may be pivoted to an inverted or upright position and again secured by attachment of the bracing elements at 30 means 14. As viewed in Figs. 1 and 2, the left hand pair of leg elements 12 carry therebetween a curved plate 15 which, in the position for packaging of the machine, is moved in to position to act as a protective shield for the power head 8.

35 By preference the shallow tank 11 is arranged to have its longitudinal side walls, act as means defining a guide-way for the article supporting carriage 10, and in which the upper edges 16 of the side walls are engaged by carriage rollers 17 40 suitably mounted on the carriage platform 18. This platform is provided with a stop plate 19 at the front, transverse margin thereof to engage the object or block A and effect movement thereof with the platform.

45 The table structure 7 is provided with laterally spaced and upstanding pedestal members 20 suitably formed of sheet metal and rigidly secured to the tank side walls near the rear end wall 21 thereof, as shown in Figs. 1, 2, 3, and 5. Each 50 such member 20 is notched at 22 in its upper end for the operative support of a shaft 23 extending therebetween. This shaft is freely bearinged in each notch 22 and carries at one end a fixed and depending sector plate 24 which 55 is adapted to move close to the inner surface of

the adjacent pedestal member 20 for releasable clamped engagement between such member and a clamp bar 25. The clamp bar 25 is secured at its lower end to the member 20 in spaced relation therewith by any suitable means, while its upper end is threadedly engaged by a clamping element 26, the latter extending through member 20 to the exterior thereof for ready accessibility and for receiving a clamp actuating handle 27. Thus the shaft 23 may have a limited range of rotational adjustment as provided by the sector plate 24, and may be secured against angular displacement upon appropriate movement of handle 27 to draw the bar 25 into position clamping the sector between its upper end 28 and the adjacent surface of the pedestal member 20 (Fig. 5).

The shaft 23 also carries a bracket member or arm 30 which is fixedly secured thereto by a pin element 31 (Fig. 4) such that arm movement is obtained concurrently with rotational displacement of the shaft. The outer free end of arm 30 is suitably flattened, as at 32, for engagement with the under surface of the top wall 33 of a rotary cutter supporting and operating arm structure 34 constituting a part of the cutter head assembly 9, before noted. Arm structure 34 is of sheet metal construction having an open and enlarged upper end beyond which side wall extensions 35 project to provide spaced and depending portions 36 for support on and free movement relative to shaft 23 (Figs. 4 and 5). The arm structure 34 tapers gradually toward its opposite end 37 at which end a shaft 38 is operatively mounted in transverse position. At one side of the arm structure 34 a generally circular housing assembly 39 (Fig. 6) is secured in position over the projecting end 40 of the shaft and upon which a cutter disc mounting hub 41 is detachably secured. The hub 41 may be of any well-known type suitable for permitting interchangeability of cutter discs, similar to the one shown at 42 in Figs. 1 and 3. The ready changing of such cutter discs is facilitated by the provision of hingedly attaching a part 43 of the housing assembly 39 for enabling its movement to an out-of-the-way position exposing more completely the shaft end 40 and cutter mounting hub 41.

The opposite end of shaft 38 from the cutter disc carries a pair of speed-change pulleys, the pulley 44 being larger than pulley 45 and hence the low-speed one of the pulley set. Access to the pulleys may be had through the hingedly mounted cap 46 (Figs. 1 and 3).

Since the tapered arm structure 34 is freely movably supported on shaft 23, its position relative to the object or block A on the carriage 10 and path of movement of the block through the zone of the cutter disc 42 is effectively provided by the bracket arm 30 (Figs. 1, 3 and 4). In the present embodiment the cutter disc floats, or, is permitted to rise and fall relative to the carriage to compensate for inequalities or variations in cutting loads imposed on the cutter disc even though the operating arm structure 34 is initially fixed in an adjusted position. This improvement is carried out by arranging the bracket arm 30 in fixed relation to shaft 23 and by the provision of a resilient or floating connection between its end 32 and the arm structure 34. Accordingly the end 32 of the arm is apertured to receive an elongated and inwardly extending attachment element 47 having an exposed, knurled end 48 for effecting adjustments in the compressive loading of an internal spring member 49, as by the threading displacement of nut 50 along the axis

of the element 47 to increase or decrease the spring compression against the under side of the arm 32 and thereby regulate the loading on cutter disc 42. The nut 50 is prevented from rotating by the provision of an elongated stop element 51 suitably secured to the structure 34 (Fig. 4). In conjunction with the load regulating means just described, the resilient or floating connection between bracket 30 and arm structure 34 is effectively stabilized by a guide element 52 extending from an exterior regulating knob 53 through the flattened end 32 of the bracket to have threading engagement with an axially movable but non-rotative nut 54. Non-rotativeness of the latter being achieved by its abutment against the flat face of notch 55 in the bracket 30. Thus element 52 may be turned to move the nut 54 into or away from the arm 32 to regulate the degree of relative pivoting or break-away movement of the operating arm structure 34. Regardless of the extent to which the spring 49 will permit break-away movement of the structure 34 during cutting action of the disc 42, the resulting movement or floating action will be checked at such time as the nut 54 abuts the flattened end 32 of the bracket 30 or otherwise establishes a solid connection between the bracket and the wall 33 of the arm structure. Normally then the arm structure 34 will be held or maintained fixed against the bracket end 32 when the machine is inactive and hence initial desired positional adjustments thereof may be obtained by releasing the clamping member 25 and resetting it when the desired position is reached. Thereafter, and during active cutting of an object such as the block A (Fig. 1) the compression spring 49 will act to load the cutter disc and maintain it in the initial desired cutting position except under excessive loads, as when the feed of block A is too rapid or its composition exhibits spots or zones of greater hardness or density of a character to decrease the rate of cutting by the disc 42. Under the latter conditions the operating arm 34 will automatically move into its floating position and remain so until the feed is reduced or the zone of increased density has been cut through.

Rotative operation of the cutter disc 42 is obtained through the provision of an electric motor 57 secured to a supporting frame structure 58, in turn carried on the shaft 23 for relative movement with respect thereto. The motor supporting frame structure is carried on the shaft 23 (Figs. 3, 4 and 5) between the side extensions 35 of the arm structure 34 and in position to have a set of speed selector pulleys 59 and 60 mounted on its projecting shaft 61 in alignment with the respective pulleys 44 and 45 on cutter operating shaft 38. The pulley 59 is larger than its companion pulley in order to provide a high rotative speed at the shaft 38 through connection with pulley 45 thereon. A single V-type belt 62 is provided and may be shifted from one set of pulleys 45 and 59 for high speed to the other set of pulleys 44 and 61 as shown in Fig. 3, for low speed.

The present mounting arrangement for the motor 57 makes use of its overhanging relation to apply a continuous tensioning load on the V-belt 62 in all positions of angular adjustment and floating movement of the operating arm structure 34, as above noted. Thus, in effecting a shift of the belt for selection of one or the other set of speed pulleys, it is necessary to elevate the motor to gain sufficient slack in the belt.

In conjunction with the present mounting arrangement of the drive motor, the supporting structure 58 therefor (Figs. 1 and 4) is provided

with a wall 63 which acts as an abutment for an adjustable stop element 64. The latter element is threadedly mounted in a nut 65 which is welded to a wall portion 66 of the projecting portions 36 of the operating arm structure 34. A lock nut 67 is provided to secure the stop element 64 in adjusted position. In this manner the position of the motor 57 and its supporting structure 58 can be selected for proper tensioning of the drive belt 62. Thus, the motor mounting 58 may be raised to an arcuate path about the fixed shaft and relative to the cutting head, whereby to loosen the drive belt 62, as for belt changing purposes, but its downward movement is limited by engagement with the end of the belt tension adjustment bolt 64, the weight of the motor mounting assembly, of course, maintaining the belt under tension. It will appear that the weight of the motor acting on one side of the shaft 23 tends to counterbalance the weight of the cutting head on the opposite side.

The present machine is also suitably provided with a fluid spray system for bathing the cutter disc to suppress dust. This system includes a fluid circulating pump 69 (Fig. 1) suitably mounted on tank wall 21 and operated by an extensible belt 70 from a drive pulley 71 mounted on the shaft 61 of motor 57 (Figs. 1 and 5). The pump has its suction pipe 72 directed into the tank 11, while the delivery conduit 73 extends upwardly and over the pedestal assembly for connection with a flow divider fitting 74 (Fig. 3) such that fluid pumped thereto will flow through each of the lateral feed lines 75 and 76 to suitable spray head (not shown) positioned internally of the cutter disc housing 39 and at each side of the cutter disc. The fluid leaving the cutter disc runs over the carriage 10 and is collected in the tank 11 for return to the pump suction pipe 72 and re-use. When desired the fluid may be drained from the tank 11 through a bottom drain fitting 77 (Fig. 1). In conjunction with the above described fluid circulating system the machine is provided with a splash guard 78 at the rear of the tank 11 and an overhanging guard 79, at one side of the upper end of the arm structure 34 (Figs. 3 and 5).

In view of the above detailed description, the operation of the present machine should now be apparent. However, for purposes of completeness the operation is described as follows:

Initially, the cutting head is adjusted to set the cutter disc for the desired depth of cut, and this involves an angular adjustment of shaft 23. Thereafter the shaft 23 is immobilized by means of the clamping assembly identified with clamp handle 27 so that any angular movement of the cutting head will be relative to the shaft. Such relative movement of the cutting head in a direction to raise the same is opposed by spring 49, and the range of relative movement is limited by the setting of the stop nut 54 by knob 53. When using certain types of cutting discs a non-yieldable mounting is preferred, in which event the stop nut 54 is drawn up tightly against portion 32 of arm 30. The more usual practice, however, is to set the clamping knob 53 to allow for upward displacement of the cutting head, and to adjust spring 49 by knob 48 to place the spring under initial compression. The degree of initial spring force determines the yieldability of the cutting head, and the proper setting of this factor will depend upon the density of the material to be cut.

As the masonry block or other object to be cut

is fed into the rotating disc 42, the latter tends to ride up the object, but such movement is opposed by the spring 49. By alternately pressing the object toward the blade 42 then relaxing the forward pressure, the blade moves in an oscillating fashion up and down in the cut groove until the cut is completed. This has proved to be a very efficient and effective cutting action.

While the present embodiment is that of a preferred machine, it should be understood that modifications, rearrangements and possible variants may be suggested after a full understanding of this disclosure and it is the aim to cover all such variants and equivalent structures within the scope of the claims hereto appended.

What is claimed is:

1. In a machine of the character described, a frame structure defining a guide-way, a work supporting and feeding carriage movably mounted on said guide-way, a rotary cutter, an operating arm for said rotary cutter enabling positionment of the latter in the path of movement of the work on said carriage, means for mounting said operating arm on said frame for selective positionment thereof relative to the work on said carriage, a power head mounted on said frame and operatively connected with said rotary cutter, said power head being arranged to move, independently of said operating arm to maintain its connection with said rotary cutter relative to selected positions of said operating arm, and means affording a resilient connection between said operating arm and mounting means therefor, whereby said operating arm during work cutting operation of said rotary cutter may have a relative floating movement to compensate for work feed variations and variations in cutting loads.

2. In a machine of the character described, a frame structure defining a guide-way, a work supporting and feeding carriage movable over the guide-way, a cutter, an operating arm for said cutter enabling positionment of the latter in the path of work feeding movement of said carriage, means for mounting said operating arm on said frame for selective positionment relative to the work on said carriage, a power head carried on said frame and operatively connected with said cutter, said power head being arranged for movement independently of said operating arm to maintain its connection with said cutter relative to selected positions of said operating arm, means for releasably securing said mounting means for the operating arm in a selected position, and means affording a floating connection between said operating arm and mounting means therefor, whereby during operation of said cutter, the same may move in a direction to compensate for work feed variations and variations in cutting loads.

3. In a machine for cutting ceramic or masonry objects, a frame defining a guide-way, an object supporting and feeding carriage movable along the guide-way, a pedestal assembly on said frame, a shaft rotatively bearinged in said pedestal assembly, means for selectively fixing its position of rotative displacement, arm means fixed on said shaft to move therewith, a cutter, means operatively supporting said cutter on said arm means for limited floating movement relative thereto, and a power head mounted on said shaft and having an operating connection with said cutter, said power head mounting affording independent movement thereof relative to said shaft for effectively maintaining its connection with said

cutter during movement of the latter when in operation.

4. In a machine for cutting ceramic or masonry objects, a frame defining a guide-way, an object supporting and feeding carriage movable along the guide-way, a pedestal assembly on said frame, a shaft rotatively bearinged in said pedestal assembly, means for selectively fixing its position of rotative displacement, a cutter, means to support said cutter on said shaft for movement relative thereto, a power head connected to said cutter and having support on said shaft for movement relative thereto, and means movable with said shaft and having a connection with said cutter supporting means for determining, upon displacement of said shaft, an initial selected position of said cutter in the path of feed of an object on said carriage, said connection between said last means and the cutter supporting means being of a character to permit a limited floating movement of said cutter to compensate the latter for variations in feed and cutting loads of the object on said carriage.

5. In a machine as set forth in claim 4, and in which said connection between said last means and the cutter supporting means is of a resilient character to permit a limited floating movement of said cutter supporting means and cutter to compensate for excessive rates of feed of the object on said carriage and for variations in cutting loads.

6. In a machine for cutting ceramic or masonry objects, a frame having a guide-way, an object-supporting and feeding carriage movable along the guide-way, a pedestal assembly on said frame, a shaft rotatively bearinged in said pedestal assembly, a clamping means for selectively fixing its position of rotative displacement, a cutter, means to support said cutter on said shaft for movement relative thereto, an arm fixed on said shaft and resiliently connected with said cutter supporting means to permit a limited degree of movement of the latter relative to the selected fixed position of said shaft, means for adjusting said resilient connection to alter the degree of movement afforded thereby, and a cutter operating

power head carried on said shaft for movement independently thereof to permit continuance of cutter operation during relative movement thereof at said resilient connection.

5 7. In a machine of the rotary cutter type, a frame structure arranged to define a guide-way, a work supporting carriage movable over said guide-way to effect feeding of the work thereon, a pedestal assembly on said frame formed to provide spaced bearings, a shaft rotatably mounted in the pedestal bearings, a cutter, means operatively mounting said cutter on said shaft in work cutting relation with said carriage and for movement relative to said shaft, a power head independently movably mounted on said shaft and operatively connected with said cutter, movement of said cutter mounting means being attended by movement of said power head in a manner maintaining the cutter operating connection therebetween, an arm member fixed on said shaft, first means adapted to connect said arm member and cutter mounting means for limited relative movement, second means of resilient character affording a connection between said arm member and cutter mounting means for normally maintaining the same against relative movement, and clamp means adapted to fix said shaft against rotation and determine the position of said fixed arm member; said first and second connecting means being arranged to determine the initial position of said cutter mounting means and provide for floating movement thereof relative to said fixed arm member and shaft to compensate for work feed variations and variations in cutting loads.
